INVENTOR

Thomas Benfield,
BY George Cook.
ATTORNEY.

UNITED STATES PATENT OFFICE.

THOMAS BENFIELD, OF NEWARK, NEW JERSEY.

DESIGN FOR A WATCH-CASE.

SPECIFICATION forming part of Design No. 21,478, dated April 19, 1892.

Application filed March 17, 1892. Serial No. 425,361. Term of patent 7 years.

To all whom it may concern:

Be it known that I, THOMAS BENFIELD, a subject of Her Majesty the Queen of Great Britain, residing at Newark, in the county of 5 Essex and State of New Jersey, have invented and produced a new and original Design for Watch-Cases, of which the following is a specification, reference being had to the accompanying drawings, forming a part thereof.

Figure 1 is a plan view of a watch-case, showing my design. Fig. 2 is a sectional view thereof, taken on the line X X of Fig. 1.

The leading or essential feature of my design consists of a watch-case provided with a 15 series of radial grooves or corrugations A, concave in cross-section, as shown in Fig. 2, and also with the radial ribs or corrugations B, con-

vex in form, said corrugations being disposed or arranged as shown in Fig. 1, one portion C of the lid being left plain. The several portions may, it is manifest, be engraved, chased, or otherwise ornamented as desired. 20

It is apparent that this design is also applicable to lockets and other similar articles.

Having described my invention, what I 25 claim as new, and desire to secure by Letters Patent, is—

The design for a watch-case, as herein shown and described.

THOMAS BENFIELD.

Witnesses:

GEORGE COOK,

WILLIAM GOEBEL.
